CLAIM

The ornamental design for a device for level measurement, as shown and described.

DESCRIPTION

FIG. 1 is a line drawing evidencing a left side view of the design;

FIG. 2 is a line drawing evidencing a top side view of the design;

FIG. 3 is a line drawing evidencing a front view of the design;

FIG. 4 is a line drawing evidencing a bottom view of the design;

FIG. 5 is a line drawing evidencing a back view of the design;

FIG. 6 is a line drawing evidencing a perspective view of the design; and,

FIG. 7 is a line drawing evidencing a right view of the design.

The broken lines shown in the drawings depict portions of the device for level measurement that form no part of the claimed design.

1 Claim, 7 Drawing Sheets
